UNITED STATES PATENT OFFICE.

CHARLES W. UPRIGHT, OF LEWISTOWN, ILLINOIS, ASSIGNOR OF ONE-HALF TO ERNEST H. RUCKER, OF LEWISTOWN, ILLINOIS.

MIXING-MACHINE.

No. 886,899.

Specification of Letters Patent.

Patented May 5, 1908.

Application filed October 30, 1907. Serial No. 399,848.

To all whom it may concern:—

Be it known that I, CHARLES W. UPRIGHT, a citizen of the United States, residing at Lewistown, in the county of Fulton, State of Illinois, have invented certain new and useful Improvements in Mixing-Machines; and I do hereby declare the following to be a full, clear, and exact description of the invention, such as will enable others skilled in the art to 10 which it appertains to make and use the same.

This invention relates to mixing and beating machines and has for its object to provide a machine of this class which may be 15 used in the several operations of mixing dough, beating eggs, etc.

The primary feature of the invention resides in so constructing the machine that all 20 of the parts may be detached one from the other and the entire machine thoroughly cleansed, this being necessary owing to the number of different uses to which it may be put.

In the accompanying drawings, Figure 1 is 25 a side elevation of the machine, Fig. 2 is an end view thereof, Fig. 3 is a vertical longitudinal sectional view therethrough, Fig. 4 is a top plan view thereof with the cover removed, Fig. 5 is a detail vertical transverse 30 sectional view through the machine, and, Fig. 6 is a detail perspective view of one of the dashers removed from the machine.

As shown in the accompanying drawings, 35 the machine comprises a supporting frame which consists of side bars 7 and end bars 8, the latter having their end portions turned at right angles as at 9 and bolted to the ends of the said side bars 7 as indicated at 10. The bolts 10 which secure the ends of the side 40 bars to the right angularly turned ends of the bars pass also through the upper ends of legs or standards 11 which standards are provided with feet 12 by means of which they may be secured to a support. Fitted in this frame is 45 the body of the mixer and this body is formed of sheet metal and comprises sides 13 and a semicylindrical bottom 14 which is integral with the sides. In other words, the sides and the bottom are continuous. The body 50 also comprises ends 15 the edges of which

conform to the end edges of the sides and bottom of the body.

Journaled through openings in the ends and through bearings 16 formed in the end bars 8 are the ends of a shaft 17 which is 55 squared throughout its length with the exception of its ends which are cylindrical at their points of bearing. Fixed to one end of this shaft is a crank handle 18 by means of which the shaft may be turned. 60

The dashers of the machine are in the form of blades 19 which are of spiral formation and have attached to them arms 20, the said arms being bifurcated to receive the backs of the blades and having rivets passed 65 through the spaced portions of their bifurcations and the said blades. These arms 20 are reduced at their ends which are removed from the blades and the reduced portions of the handles are threaded as indicated at 21 70 and engaged through openings 22 formed through the body of the shaft 17, there being thumb nuts 23 engaged upon the said threaded ends of the arms to secure them to the shaft. A cover 24 is provided for the 75 body of the mixer and this cover is entirely removable and is provided with a handle 25 by means of which it may be so removed.

From the foregoing description of my invention it will be seen that the machine may 80 be taken apart for cleaning, one part from the other and that no tools are required for this purpose.

What is claimed, is—

A machine of the class described comprising 85 a supporting frame, a body supported by the frame, a shaft journaled longitudinally in the body, said shaft being formed with openings, arms provided with reduced threaded ends engaged in the openings in the shaft, 90 thumb nuts engaged upon the said ends of the arms, the other ends of the arms being bifurcated, and spiral blades fixed in said bifurcations.

In testimony whereof, I affix my signature, 95 in presence of two witnesses.

CHARLES W. UPRIGHT.

Witnesses:

W. B. GILLAM,
E. J. HUGHES.
